US00D997936S

(12) **United States Design Patent** (10) **Patent No.:** **US D997,936 S**
Tu (45) **Date of Patent:** **** Sep. 5, 2023**

(54) **LAPTOP COMPUTER**

(71) Applicant: **Lenovo (Beijing) Limited**, Beijing (CN)

(72) Inventor: **Chuantao Tu**, Beijing (CN)

(73) Assignee: **Lenovo (Beijing) Limited**, Beijing (CN)

(**) Term: **15 Years**

(21) Appl. No.: **35/515,142**

(22) Filed: **May 5, 2022**

(80) **Hague Agreement Data**

Int. Filing Date: **May 5, 2022**

Int. Reg. No.: **DM/223197**

Int. Reg. Date: **May 5, 2022**

Int. Reg. Pub. Date: **Sep. 16, 2022**

(30) **Foreign Application Priority Data**

Dec. 28, 2021 (CN) 202130867563.1

(51) **LOC (14) Cl.** **14-02**

(52) **U.S. Cl.**

USPC **D14/327**; D14/315
